INK PADS

Theodor Rommel and Karlheinz Behnke, Hannover, Germany, assignors to Gunther Wagner, Hannover, Germany, a firm

Application May 31, 1955, Serial No. 512,042

Claims priority, application Germany June 2, 1954

2 Claims. (Cl. 118—264)

The invention relates to an ink pad and is characterized in that it consists of a bottom drawn metal part, a holder frame of plastic or similar material placed on the bottom part and a drawn sheet metal lid.

Various constructions of ink pads are known but, in spite of all endeavours, have not hitherto produced an article which gives satisfaction from a manufacturing, economical, practical and aesthetic point of view, as any improvement in one respect is counteracted by disadvantages in other respects. In the most common type of ink pad on the market with top and bottom parts made of sheet metal, the main objection is that the sharp, open corners are dangerous, unsightly and do not close tightly. To prevent corrosion the pad itself must be placed in a trough or dish of oil paper, but even this does not produce a perfectly tight seal at the corners. But also from the point of view of manufacture and economy these ink pads have serious disadvantages as their production requires numerous operations which results in a disproportionately high priced pad. Therefore these ink pads must be regarded as unsatisfactory from all four points of view.

Consequently there has been a partial change over to the use of plastic material for making the boxes, thereby overcoming all objections except that of economy. As the cost of these plastic materials is almost twice that of sheet iron, the price of these ink pads is so high that they can only come into question for private use but not for general use. All attempts to overcome the disadvantages of sheet metal boxes without having to put up with the high price for plastic boxes can be considered as a failure, for it has not been possible to eliminate all the objections.

It has now been found that by the means proposed by the invention, it is possible to avoid all the objections of the ink pads hitherto known in a simple manner without having to put up with any other objections. By using drawn lids and bottom parts it has first become possible to produce both parts with closed rounded corners and also with rounded edges much more simply from a manufacturing point of view. However, not only this advantage is attained, but at the same time the economical question is substantially solved and moreover the practical problem is basically improved by closing the corners. In addition the appearance of the ink pad is more attractive and better adapted to modern taste so that this also represents a considerable enhancement of its staple use.

The result is that by these features alone all four of the objections mentioned at the outset can be considered as eliminated.

The employment of the plastic holder frame attains its object without, however, introducing any of the other objections. In the case of the drawn bottom part a sharp upper edge is produced which must be done away with by some means or other, which normally could only be by beading. This operation, however, presents con-

2

siderable difficulty at the corners because the material tears. Moreover this beading would be useless from a practical point of view owing to the fact that the rounded edges of the bottom part in any case make it impossible

5 to utilize the entire surface of the pad as an effective inking surface for the stamp, seeing that when the stamp is pressed directly on to the border of the inking surface, the pad, due to the rounded edges of the bottom part, can easily be tipped. Consequently the useful inking surface must be defined in any case. In this connection the frame presents the double advantage that on the one hand it covers the sharp edge and on the other hand it defines the useful inking surface, because it will only be made of such a width that the inking surface lies above the level part of the bottom surface of the bottom part.

Another advantage of the plastic frame is that the cloth cover of the inking pad can be easily fixed. Hitherto the cloth cover was either wrapped round the support and firmly stuck on the under side thereof or 20 firmly held with the aid of a clip or snap ring. This can now be attained by applying to the underside of the frame before it is placed on the bottom part, a substance which dissolves the upper surface of the plastic frame, which substance, when the frame has been fitted, 25 is in intimate contact with the cloth cover and binds this tightly on the frame as soon as the solvent has evaporated.

Another simple means of fixing the ink carrier with the aid of the holder frame is to place the ink carrier 30 on a block of cardboard, wood or the like, interposing a thermoplastic foil between the frame and the carrier, the edge zones of the fabric cover of the ink carrier are then rigidly connected to the border zones of the foil and the supporting block by the application of heat, 35 utilizing the thermoplastic properties of the foil.

The supporting block in this case is preferably of such a height that, after the holder frame has been pressed into position, the lower inner edge thereof presses the boundary zone of the fabric cover firmly secured 40 to the thermoplastic foil, on to the supporting block. Thus the supporting block is at the same time pressed against the sheet metal bottom part so that, with the aid of the holder frame, the whole inserted aggregate is held in the sheet metal bottom part and secured against falling out.

So as to ensure against every possibility imaginable of ink penetrating into the bottom part, the thermoplastic foil can be made so much larger than the base surface of the ink pad that, when the assembled ink carrier is inserted in to the bottom part, it bends upwards 45 on the walls thereof, so that the fabric cover, which is at the most the same size as the foil, does not come into contact with the wall of the bottom part. The foil and fabric cover form as it were a trough or dish located in the bottom part which, even if the ink should ooze 50 into the dish, positively prevents it from passing into the bottom part. When it is stated above that the fabric cover should be at the most the same size as the foil, this means that the cloth cover is normally smaller than the foil.

60 Instead of placing the ink carrier provided with its fabric cover on to a block of cardboard, wood or the like with an interposed foil of thermoplastic material, the ink carrier can also be placed on the block of cardboard, wood or the like without interposing any insulating material and the block placed on a thermoplastic foil. Just as in the case where the thermoplastic foil is introduced between the ink carrier and the block, the boundary zones of the fabric cover of the ink carrier are firmly connected with the boundary zones of the thermoplastic foil by the application of heat, utilizing the thermoplastic properties of the foil so that a complete aggregate is produced which

65

can be inserted as a whole in the ink pad case. Similarly, the fabric cover and the foil can be so large that the interconnected boundary zones form a holding or retaining border or frame extending over the ink pad surface.

This does not, however, exhaust the advantages of the plastic frame.

When making ink pads of different colors it was hitherto necessary to mark the box by suitable printing. This also necessitated a separate operation and keeping a relatively large stock of semi-finished products. The plastic frame also does away with this objection because, instead of making the boxes in different colors, it is only now necessary to keep in stock different colored plastic frames, the appropriate coloring being incorporated in the plastic mass. The color of the frame shows the user the color of the ink pad. All sheet metal parts and the printing thereon can be in some neutral color. The fact that corrosion phenomena are eliminated by the plastic frame need not be further emphasized.

The lid can be mounted on the holding frame, for example, by means of eyes or rolls provided on the frame, hinge rolls formed on the lid and a hinge pin threaded through these rolls. It might, however, be mounted on the sheet metal bottom part, in which case this would be provided with hinge lugs extending through slots in the holder frame, which lugs, after the holder frame has been placed on the bottom part, are bent over to form hinge rolls and in conjunction with the known hinge rolls on the lid and the hinge pin, form the hinge joint for the lid.

The holder frame can be fixed on the bottom part in a simple manner in that the frame, which is of U-shaped section on its under side, is slipped over the edge of the bottom part with the inner side of the outer U-arm fitting tightly against the outer side of the bottom part. If it is desired to fix more firmly, resilient lugs can be bent inwards on one or several sides of the bottom part so that, when the holder frame is placed on the bottom part, these lugs resiliently engage the U-section on the underside of the holder frame and hold this tightly on the bottom part.

In brief, therefore, an ink pad is produced according to the invention which represents a considerable improvement as compared with the known ink pads from the points of view of production, economy, practicability and appearance.

Several embodiments of the invention are illustrated by way of example in the accompanying drawings, in which:

Fig. 1 shows an ink pad in front elevation;

Fig. 2 is a top plan view of Fig. 1;

Fig. 3 shows on an enlarged scale an ink pad partly in elevation and partly in section on line III-III of Fig. 2;

Fig. 4 is a top plan view of a special construction of the holder or retainer frame;

Fig. 5 is a similar sectional view to Fig. 3, showing the rear portion of the pad on an enlarged scale;

Fig. 6 is a section taken on line VI-VI of Fig. 2 of a form of construction such as that illustrated in Fig. 5;

Fig. 7 is a similar sectional view to Fig. 3 showing a modified form of construction, and

Figs. 8 and 9 are sections showing forms of construction of an ink carrier aggregate.

As shown in Figs. 1 and 2, the ink pad consists of a bottom part *a*, a frame *b* mounted thereon and a lid *c* provided in known manner with a handle *e* for opening the lid.

According to Fig. 3, the lid *c* is attached by eyes *d* formed on the holder frame, a hinge roll *n*, formed on the lid in known manner and a known hinge pin *o*. Figs. 4 to 6 show another manner of attaching the lid *c*. In this construction the bottom part *a* is provided with hinge lugs *k* which pass through slots *l* in the holder frame *b* and, after the holder frame *b* has been placed on the bot-

50

tom part *a*, are bent to form hinge rolls *m* which with the hinge roll *n* on the lid *c* and hinge pin *o* form the hinge.

Fig. 3 shows the manner in which the holder frame *b*

55 is attached to the bottom part *a* in that the under side of the holder frame *b* has a U-shaped section which is slipped over the edge of the bottom part *a* and sits tightly thereon. In Fig. 7 another method of attachment is shown wherein the bottom part *a* has a resilient lug *p* which is bent inwards in such a manner that, when the holder frame *b* is placed on the bottom part *a*, this lug resiliently engages in the U-section on the under side of the holder frame and thus holds the holder frame *b* firmly in position on the bottom part *a*.

As can be seen from Figs. 3, 5, 6 and 7, the holder frame *b* extends inwards so far that the useful surface of the ink pad lies above the level of the bottom surface of the bottom part *a* so that the pad itself cannot possibly tip if the stamp is placed on the extreme edge of the inking surface.

20 The ink pad proper, as shown in Figs. 3 and 5, consists of an ink carrier *f* and a fabric cover *i* stretched over the ink carrier *f*. In the construction illustrated in Fig. 3, the ink carrier *f* is composed of felt or some other suitable material embedded in a dish *g* of cardboard impregnated with plastic and in turn resting in known manner on a support of wood, pasteboard or the like. The fabric cover *i* extends downwards between the frame *b* and the dish *g* and is stuck on to the inner side of the holder frame *b*. This prevents the ink from oozing into the bottom part *a*.

25 Should it be desired to take greater precautions to prevent the ink from oozing into the bottom part *a* and the corrosion resulting therefrom, the arrangement shown in Fig. 5 may be selected. Instead of the dish made of cardboard steeped in plastic, a thermoplastic foil *r* is placed between the ink carrier *f* and the block *h*. The boundary zones of the fabric cover *i* are then firmly connected with the boundary zones of the foil *r* and of the

30 supporting block *h* by the application of heat, taking advantage of the thermoplastic properties of the foil. The arrangement should preferably be in the form shown in

35 Fig. 3, wherein the supporting block *h*, thermoplastic foil *r* and fabric cover *i* extend on all sides beyond the ink carrier *f* and the supporting block *h* is of such height that, when the holder frame *b* has been pressed into

40 position, its lower inner edge presses the boundary zone of the fabric cover *i*, rigidly connected to the thermoplastic foil *r*, tightly on to the supporting block *h*. In this

45 manner the ink in the ink carrier *f* is reliably sealed off so that it cannot penetrate into the bottom part *a* of the ink pad.

50 To anticipate the possibility that ink might ooze into the bottom part *a* along the path extending over the portion of the fabric cover *i* bearing against the inner side of the frame *b* between the lower inner edge of the frame *b* and through the boundary zone of the fabric cover *i* firmly connected to the foil *r* and the supporting block *h*, the

55 thermoplastic foil *r* may be made so much larger than the base surface of the bottom part *a* that, when the assembled ink carrier is inserted in the bottom part, it will be bent upwards on the wall thereof. Thus a kind of trough or dish is formed, the upwardly extending edge *s* of which is formed by the extreme zones of the foil *r* and the cover *i*.

60 At the same time the cover *i* should not be larger than and preferably smaller than the foil *r* so as to exclude as far as possible all possibility of the ink being transferred from the cover *i* on to the wall of the bottom part *a*.

65 Should ink enter the dish, it in any case will remain therein.

In the forms of construction of the ink carrier aggregate

65 shown in Figs. 8 and 9, the ink carrier *f* carrying the fabric cover *i* is placed on the block *h* without any intervening layer of insulating material and the block *h* is placed

70 on a thermoplastic foil *r*. In the construction shown in

75 Fig. 8 the foil *r* is bent upwards at the edges and its

boundary zones are firmly connected by heating with the boundary zones of the fabric cover *i* extending over the block *h*. In the form of construction illustrated in Fig. 9 the foil *r* and fabric cover *i* are of such size that the boundary zones, also firmly interconnected by heating, form a holder frame projecting beyond the inking surface of the pad, which frame can be used in a similar manner to the edge in the construction shown in Fig. 5, when this edge will then rest directly on the bottom of the ink pad box and be bent up on the side wall thereof.

We claim:

1. An ink pad comprising an integrally formed bottom part, a frame carried on said integrally formed bottom part, and an ink carrier aggregate disposed within said frame holder, at least one eye projecting from said frame holder, a cushion having a fabric cover stretched over said ink carrier aggregate, a block supporting said cushion, a thermoplastic foil material interposed intermediate said cushion and said block, said fabric cover having edge zones firmly connected to said foil and said block, said thermoplastic foil being larger than the base surface of said bottom part when said ink carrier aggregate is inserted in said integrally formed bottom part and is bent upward on the walls of said bottom part so that the fabric cover which is not larger than the foil does not come into contact with the wall of the integrally formed bottom part,

and a lid covering said frame holder and said ink carrier aggregate.

2. An ink pad comprising an integrally formed bottom part, a frame holder carried by said bottom part, an ink carrier aggregate disposed within said frame holder, a sheet lid covering said frame holder and said ink carrier aggregate, a cushion having a fabric cover stretched over said ink carrier aggregate, a block supporting said cushion, a thermoplastic foil material interposed intermediate said cushion and said block, edge zones of said fabric cover and edge zones of said foil being firmly fused to each other, said fused edge zones forming a holding edge of such width so that when the ink carrier aggregate is placed in the integrally formed bottom part of the ink pad, the border bends upward on the wall of the bottom part so that the fabric cover, the size of which is not greater than that of the foil does not come into contact with the walls of the bottom part.
